UNITED STATES PATENT OFFICE.

DANIEL A. BEAM, OF NEWARK, NEW JERSEY, ASSIGNOR TO WHEELER,
PARSONS & HAYES, OF SAME PLACE.

DESIGN FOR AN ORNAMENTAL CHAIN-LINK.

SPECIFICATION forming part of Design No. 11,824, dated June 15, 1880.

Application filed April 6, 1880. Term of patent 7 years.

To all whom it may concern:

Be it known that I, DANIEL A. BEAM, of the city of Newark, in the county of Essex and State of New Jersey, have invented and produced a new and original Design for a Chain-Link, of which the following is a specification, reference being had to the accompanying drawings, forming part thereof.

Figure 1 represents a face view of a chain-link of my design. Fig. 2 is an edge view of the same. Fig. 3 is a side view of a piece of chain composed of a number of such links enclosed together to form a chain.

The link has its faces flat, or approximately so, and of a nearly circular contour, being composed of larger and smaller circular concentric parts A B, less than complete circles, united by divergent straight and nearly radial parts C C. The inner circular part, A, and the

straight parts C C have their edges plain, as 20 in links of the same general form heretofore known; but the inner and outer edges of the outer circular part, B, instead of being plain, as in those links, are so scalloped that the profile of the scalloping of either edge forms portions of a number of small circles, a a, of which the profile of the scalloping of the other edge forms corresponding portions. 25

What I claim is—

The design for a chain-link herein shown 30 and described, consisting of the inner circular part, A, the straight parts C C, and the outer circular part, B, scalloped to form portions of small circles a a.

DANIEL A. BEAM.
